US0D1114127S

(12) **United States Design Patent** (10) **Patent No.:** **US D1,114,127 S**
Donovan (45) **Date of Patent:** **** Feb. 17, 2026**

(54) **PUTTING HOLE DEVICE**

(71) Applicant: **The Puttalite Company Limited**,
 Stoke on Trent (GB)

(72) Inventor: **Michael Kevin Donovan**, Stoke on
 Trent (GB)

(**) Term: **15 Years**

(21) Appl. No.: **35/523,516**

(22) Filed: **Jan. 10, 2024**

(80) **Hague Agreement Data**

Int. Filing Date: **Jan. 10, 2024**
 Int. Reg. No.: **DM/236211**
 Int. Reg. Date: **Jan. 10, 2024**
 Int. Reg. Pub. Date: **Jan. 10, 2025**

(51) **LOC (15) Cl.** **21-02**
 (52) **U.S. Cl.** **D21/791**

Primary Examiner — Mitchell I. Siegel

(57) **CLAIM**

The ornamental design for putting hole device as shown and described.

DESCRIPTION

1. Putting hole device

- 1.1** : Perspective
1.2 : Front
1.3 : Top
1.4 : Bottom
1.5 : Left
1.6 : Right
1.7 : Back

The broken lines form no part of the claimed design.

1 Claim, 7 Drawing Sheets
